Patented Nov. 28, 1922.

UNITED STATES PATENT OFFICE.

DAVID C. HERSHBERGER, OF TURTLE CREEK, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

Application filed January 30, 1920. Serial No. 355,077.

To all whom it may concern:

Be it known that I, DAVID C. HERSHBERGER, a citizen of the United States, and a resident of Turtle Creek, in the county of 5 Allegheny and State of Pennsylvania, have invented a new and useful Improvement in Systems of Control, of which the following is a specification.

My invention relates to systems of control for dynamo-electric machines and it has 10 special relation to the protection of auxiliary apparatus on locomotives under predetermined electrical conditions of the main or car-propelling machine.

The object of my invention is to provide a 15 system of the above-indicated character whereby auxiliary translating devices or working circuits, either on a regenerative locomotive or on some other and non-regenerative locomotive, may be protected in the 30 event of an unduly high regenerative voltage.

Other objects of my invention will become 25 evident from the following detailed description, taken in conjunction with the accompanying drawing, wherein the single figure is a diagrammatic view of an alternating-current transmission and distribution system for electric railways, together with two 30 locomotives respectively of the regenerative and the non-regenerative type.

In electric-railway systems, including locomotives that are adapted for regenerative operation, it sometimes happens that, by 35 reason of traveling down a grade, for example, a voltage considerably above that of the normal supply circuit is provided by the momentum-driven machines on a locomotive of the regenerative type. Such relatively 40 high voltage may often be in excess of safe operating values for auxiliary motors, lamp circuits, etc. on the same locomotive and, also, for all of the machines and apparatus upon other locomotives which happen to be 45 running in the vicinity of the regenerative locomotive and thus receive a voltage considerably higher than the normal substation voltage. The same statements hold with respect to signal circuits which may be operated from the trolley circuit.

In particular, when the feeder conductors installed in a railway system are of relatively limited capacity, it may be necessary to provide for a comparatively large

voltage drop between a locomotive of the 55 regenerative type and a substation or other source of supply, in order to permit returning a maximum amount of energy to the line when the locomotive is descending grades or retarding its speed. This condition, of 60 course, signifies that a regenerative voltage materially in excess of the normal substation voltage is required.

Referring to the accompanying drawing, the railway system shown comprises a main 65 alternating-current three-phase generator 1 of a familiar type that is connected to a feeder or distribution circuit 2 to which a substation 3 of either the step-down or rotary converter type is connected to transform or convert the feeder voltage to a single-phase or direct-current voltage of suitable value, such as 600 volts, for operating locomotives.

The drawing diagrammatically illustrates 75 two locomotives 4 and 5, respectively of the regenerative and the non-regenerative type, that operate from a suitable supply circuit having conductors Trolley and Ground, in accordance with a customary practice.

Considering the regenerative locomotive 4, the illustrated apparatus thereon comprises a main or car-propelling motor M1 having a commutator-type armature A1 and an exciting field winding F1 of the series 85 type that is energized, during the regenerative period, from the armature 11 of a commutator-type exciter 10, the shunt field winding 12 of which is connected, through a rheostat 13 and a hand-operated switch 90 14, across the supply conductors. The exciter 10 is driven by an auxiliary motor 15 having a commutator-type armature 16 that is suitably coupled with the exciter 10, as by a shaft 17, and a series field winding 18, 95 a hand switch 19 being provided for connecting the auxiliary motor 15 across the supply circuit.

For the purpose of controlling the armature circuit of the main motor M1, a drum 100 controller 20 is shown as adapted to insert more or less of a resistor 21 in the armature circuit, as will be understood.

The auxiliary apparatus installed upon the locomotive is shown as comprising a 105 compressor motor 22 having a commutator-type armature 23 and a series field winding 24, a lamp circuit 25, and a control circuit

26 for governing the operation of various switches, or the like, included in the auxiliary control circuits for the locomotive.

It will be understood that the devices 22, 5 25 and 26 are shown for illustrative purposes only and that any other translating devices that are not adapted for safe operation from a voltage materially higher than the normal supply-circuit voltage of 10 600 volts, for example, may be installed on the locomotive to replace those shown or to be employed in addition thereto.

The protective apparatus for the auxiliary circuits comprises a resistor 27, or the like, 15 that is connected in series relation with the parallel-connected translating devices 22, 25 and 26 and which, under normal or low-voltage conditions of the supply circuit, is short-circuited by an electrically controlled 20 switch or relay 28, the actuating coil for which is governed by a voltage relay 29, which has its actuating coil directly connected to the supply-circuit conductors. Thus, under normal or low-voltage operating conditions, the voltage relay 29 occupies its 25 lower position to close the switch 28 and thus short-circuit the protective resistor 27.

The other locomotive 5 is of the non-regenerative type and includes a main or car-propelling motor M2 having a commutator-type armature A2 and a series-connected exciting field winding F2. A main-circuit protective resistor 38, which is provided for the motor M2, is normally short-circuited by a switch 35 39, as subsequently more fully explained.

The remaining apparatus upon the locomotive, numbered from 40 to 49, inclusive, corresponds to that installed upon the locomotive 4 and numbered from 20 to 29, inclusive. More specifically stated, a controller 40 governs a variable resistor 41 in the main-motor circuit, while a compressor motor 42, having an armature 43 and a field winding 44, together with a parallel-connected lamp circuit 45 and a control circuit 46, is protected from high voltage by a resistor 47 that is normally short-circuited by a switch 48. A voltage relay 49, which occupies its lower position under normal or low-voltage 50 conditions of the supply circuit, is adapted to govern both of the switches 39 and 48, whereby, under such voltage conditions, the main-circuit-protective resistor 38 and the auxiliary circuit-protective resistor 47 are 55 short-circuited.

The operation of my invention may be set forth as follows. Assuming that the proper manipulation of the main and the exciting circuits on the regenerative locomotive 4 has 60 been effected to start and maintain regenerative operation of the momentum-driven dynamo-electric machine M1, no action of the protective relay devices 28 and 29 occurs so long as the regenerative voltage remains 65 within safe limits with respect to the opera-

tion of the auxiliary translating devices 22, 25 and 26. In other words, the protective resistor 27 remains short-circuited during such normal operation.

However, upon the occurrence of a relatively high regenerative voltage, for previously explained reasons, the voltage relay 29 is actuated to its illustrated upper or open-circuit position to de-energize the actuating coil of the switch 28, which thereupon drops to its lower position to insert the protective resistor 27 in the circuit of the auxiliary translating devices mentioned. Consequently, a suitably low and, therefore, safe operating voltage is impressed upon the compressor motor 22, the lamp circuit 25 and the control circuit 26. These auxiliary circuits thus continue to function in the normal manner, irrespective of the relatively high voltage that the locomotive is impressing upon the supply-circuit conductors.

When the regenerative voltage decreases to a value approximately equal to that of the normal supply-circuit voltage, or when regenerative operation is discontinued, the voltage relay 29 will drop to its lower position to energize the switch 28. In this way, the protective resistor 27 is again short-circuited to allow the normal supply-circuit voltage to be impressed upon the circuits of the auxiliary translating devices 22, 25 and 26.

If the locomotive 5 of the non-regenerative type is running in the vicinity of the regenerative locomotive 4, so that a voltage higher than that of the normal substation voltage is being supplied to the locomotive 5, then similar protective functions are automatically performed by reason of the lifting of voltage relay 49 and the consequent opening of switches 39 and 48 to respectively insert the main-circuit protective resistor 38 and the auxiliary protective resistor 47 in series relation with the main motor M2 and the parallel-connected auxiliary translating devices 42, 45 and 46. Consequently, in this case, both the main motor and the auxiliary apparatus are fully protected from the effects of the high voltage impressed upon the supply circuit by the regenerative locomotive 4.

As soon as such voltage decreases to a normal value by reason of the cessation of regenerative action or because of the increasing distance between the locomotives, whereby the trolley-circuit-voltage drop serves to absorb the excess value of electromotive force, then the voltage relay 49 on the non-regenerative locomotive 5 will drop to its lower position to effect the energization of the switches 39 and 48 and thus again exclude protective resistors 38 and 47 from circuit.

I do not wish to be restricted to the specific circuit connections or arrangement of parts herein set forth, as various modifications

thereof may be made without departing from the spirit and scope of my invention. I desire, therefore, that only such limitations shall be imposed as are indicated in the 5 appended claims.

I claim as my invention:

1. In a system of control, the combination with a dynamo-electric machine adapted for regenerative operation, of an auxiliary 10 working circuit shunted across said machine, and means responsive to predetermined electrical conditions of said machine for materially varying the regenerated voltage applied to said working circuit.
- 15 2. In a system of control, the combination with a dynamo-electric machine adapted for regenerative operation, of an auxiliary translating device connected across said machine, and means responsive to the regenerated 20 voltage of said machine for reducing the voltage impressed upon said translating device.
- 25 3. In a system of vehicle control, the combination with a supply circuit and a dynamo-electric machine adapted for regenerative operation, of an auxiliary working circuit, a common traveling contact member for connecting said machine and said working circuit to said supply circuit, and means 30 responsive to predetermined abnormal conditions in said regenerating machine for counteracting the effects thereof with respect to said working circuit.
- 35 4. In a system of vehicle control, the combination with a dynamo-electric machine adapted for regenerative operation and located on one vehicle, of a translating device located on another vehicle, and means responsive to the regenerated machine voltage 40 for modifying the circuit connections of said translating device.
- 45 5. In a system of vehicle control, the combination with a dynamo-electric machine adapted for regenerative operation and located on one vehicle, of a translating device located on another vehicle, and means responsive to predetermined abnormal machine conditions for varying the regenerated voltage applied to said translating device.
- 50 6. In a system of vehicle control, the combination with a dynamo-electric machine

adapted for regenerative operation and located on one vehicle, of a translating device located on another vehicle, and means responsive to relatively high machine-voltage 55 conditions for reducing the regenerated voltage impressed upon said translating device.

7. In a system of vehicle control, the combination with a dynamo-electric machine 60 adapted for regenerative operation and located on one vehicle, of a translating device located on another vehicle, and means for counteracting the effects of high regenerated machine voltage with respect to said device. 65

8. In a system of control, the combination with a dynamo-electric machine adapted for regenerative operation, of a translating device connected in parallel relation to said 70 machine, and means responsive to predetermined regenerative machine conditions for modifying the condition of said translating device.

9. In a system of control, the combination with a dynamo-electric machine adapted for regenerative operation, of a translating device connected in parallel relation to said machine, a resistor, and means responsive to regenerated machine voltage for inserting 80 said resistor in circuit with said device. 75

10. In a system of control, the combination with a dynamo-electric machine adapted for regenerative operation, of a translating device connected in parallel relation to said machine, a resistor, and relay means responsive to relatively high regenerated machine voltage for inserting said resistor in series 85 relation with said device.

11. In a system of vehicle control, the 90 combination with a dynamo-electric machine adapted for regenerative operation and located on one vehicle, of a translating device located on another vehicle, a resistor, and relay means responsive to relatively high 95 regenerated machine voltage for inserting said resistor in series relation with said device.

In testimony whereof, I have hereunto subscribed my name this 21st day of January 1920. 100

DAVID C. HERSHBERGER.
